UNITED STATES PATENT OFFICE

160,589

VIEWER FOR A CONTINUOUS MOVING
STRIP OF FILMFelix Gilbert, New York, N. Y., assignor to
Benjamin J. Shapiro, New York, N. Y.

Application November 18, 1949, Serial No. 6,131

Term of patent 14 years

(Cl. D61—1)

To all whom it may concern:

Be it known that I, Felix Gilbert, a citizen of the United States and resident of the city, county, and State of New York, have invented a new, original, and ornamental Design for a Viewer for a Continuous Moving Strip of Film, of which the following is a specification, reference being had to the accompanying drawing, forming part thereof.

Fig. 1 is a front perspective view of a viewer for a continuous moving strip of film, showing my new design;

Fig. 2 is a rear perspective view thereof.

I claim:

The ornamental design for a viewer for a continuous moving strip of film, substantially as shown.

FELIX GILBERT.
